(57) **CLAIM**

The ornamental design for a square bowl with lid, as shown and described.

DESCRIPTION

FIG. 1 is a front, top isometric view of a square bowl with lid showing the new design, with the lid mounted on the square bowl;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a cross-sectional view thereof taken along lines 8-8 as indicated in FIG. 1.

The evenly spaced broken lines in the drawings depict portions of the square bowl with lid that form no part of the claimed design, including the word "goop" that is a registered U.S. trademark.
